UNITED STATES PATENT OFFICE.

LILLIAN M. ARMSTRONG, OF NEW YORK, N. Y., ASSIGNOR TO FREDERICK A. CONSTABLE AND HICKS ARNOLD, OF SAME PLACE.

DESIGN FOR A RUG OR SIMILAR ARTICLE.

SPECIFICATION forming part of Design No. 33,608, dated November 20, 1900.

Application filed October 26, 1900. Serial No. 34,509. Term of patent 3½ years.

To all whom it may concern:

Be it known that I, LILLIAN M. ARMSTRONG, a citizen of the United States, residing at the city of New York, borough of Brooklyn, 5 county of Kings, and State of New York, have invented and produced a certain new and original Design for Rugs or Similar Articles, fully described and represented in the following specification and the accompanying drawing, forming, forming a part of the same.

The design is intended to be worked into or upon rugs or similar articles in such colors as may be desired.

The leading feature of the design is the field or body portion made up of figures a 15 and crossing lines or veins b, the whole being inclosed by a border c.

What I claim is—

The design for a rug or similar article substantially as shown and described. 20

In testimony whereof I have hereunto set my hand, this 24th day of October, 1900, in the presence of two subscribing witnesses.

LILLIAN M. ARMSTRONG.
